US0D1010366S

(12) **United States Design Patent** (10) **Patent No.:** **US D1,010,366 S**
(45) **Date of Patent:** **** Jan. 9, 2024**

(54) **RETAIL FIXTURE**

(71) Applicant: **Apple Inc.**, Cupertino, CA (US)

(72) Inventors: **Allison Inouye**, San Francisco, CA (US); **Jean-Marc Gady**, Menlo Park, CA (US); **Ismael Flores Trujano**, San Jose, CA (US); **Gregory Guillaume Lespinard**, San Jose, CA (US); **Mike Zou**, San Francisco, CA (US); **Po Huang**, San Jose, CA (US); **Wesley Bryan Hamm**, San Francisco, CA (US); **Russell John Kaaihue Heirakuji**, San Jose, CA (US); **Joshua Robert Edwards**, Santa Cruz, CA (US); **Nicholas E. Corti**, San Francisco, CA (US); **Manuel Dejesus**, San Francisco, CA (US); **Alice Marlin Brugger**, Sonoma, CA (US)

(73) Assignee: **Apple Inc.**, Cupertino, CA (US)

(**) Term: **15 Years**

(21) Appl. No.: **29/878,828**

(22) Filed: **Jun. 28, 2023**

Related U.S. Application Data

(63) Continuation of application No. 29/849,845, filed on Aug. 15, 2022, which is a continuation of application No. 29/807,410, filed on Sep. 10, 2021, now Pat. No. Des. 960,616, which is a continuation of application No. 29/763,378, filed on Dec. 22, 2020, now Pat. No. Des. 930,409, which is a continuation of application No. 29/713,511, filed on Nov. 15, 2019, now Pat. No. Des. 906,026.

CLAIM

The ornamental design for a retail fixture, as shown and described.

DESCRIPTION

FIG. 1 is a top front perspective view of a retail fixture showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines in the figures show portions of the retail fixture that form no part of the claimed design.

The dot-dash broken lines in the figures show boundaries that form no part of the claimed design.

1 Claim, 5 Drawing Sheets
